UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY

ANTIFRICTION SIDE BEARING.

1,318,710.

Specification of Letters Patent.

Patented Oct. 14, 1919

Application filed February 17, 1919. Serial No. 277,518

To all whom it may concern:

Be it known that I, EDWIN W. WEBB, a citizen of the United States, residing at Chicago, in the county of Cook and State of Illinois, have invented certain new and useful Improvements in Antifriction Side Bearings; and I do hereby declare the following to be a full, clear, and exact description of the invention, such as will enable others skilled in the art to which it appertains to make and use the same.

My invention relates to side bearings for cars, of the type whereby the anti-friction member is returned to normal position by a weighted gravity-actuated member.

In experimenting with this type of anti-friction side bearings, I have found that when a roller-returning member, in the form of a pin or bolt, arranged to roll directly on guides, is used to gravity-return an anti-friction member to normal position, the same is very noisy, and, therefore, renders the entire device objectionable. To overcome this objectionable feature, I provide the roller-returning member with relatively large wheels that are in constant rolling engagement with the guides or track rails provided therefor. These wheels, by their added weight to the roller-returning member, cause the same to be more positive in its action, and also constantly hold said member on the guides, so that it will roll quietly thereon.

To the above end, the invention consists of the novel devices and combinations of devices hereinafter described and defined in the claims.

In the accompanying drawings, which illustrate the invention, like characters indicate like parts throughout the several views.

Referring to the drawings,

Figure 1 is a plan view of the improved device;

Fig. 2 is a side elevation of the same;

Fig. 3 is a vertical section taken on the line 3-3 of Fig. 1;

Fig. 4 is a vertical section taken on the line 4-4 of Fig. 1;

Fig. 5 is a transverse section taken on the line 5-5 of Fig. 2; and

Fig. 6 is a fragmentary view corresponding to Fig. 3 with the anti-friction member moved to one of its extreme positions.

The numerals 7 and 8 represent, respectively, portions of the truck bolster and

body bolster of a railway car, and the numerals 9 and 10 indicate, respectively, an upper bearing plate or surface carried by the body bolster 7 and a lower bearing plate carried by the truck bolster 8.

An anti-friction member, is interposed between the bearing surface 9 and 10 and, as shown, is in the form of a roller 11 having a large axial opening or bore 12. This roller 11 is of such diameter as to be normally out of engagement with the upper bearing plate 9 and is loosely mounted in a cast rectangular housing 13 with an open top. Cast with the lower portion of the housing 13, are three horizontally disposed ears 14 having bores 15 through which rivets or other fastening means, not shown, are passed to rigidly secure said housing to the truck bolster.

The lower bearing plate 10 rests on the bottom of the housing 13 and is held against movement in a horizontal plane by the sides of said housing and a pair of lugs 16 cast on the bottom of said housing. Rivets 17 are inserted through bores in the bottom of the housing 13 and lugs 16, and their heads overlap the ends of the bearing plate 10, and thereby hold the same against lifting movement from the bottom of said housing.

Integrally formed with the inner wall of each side of the housing 13, is an endless flange 18. The lower portions of these two flanges affords a pair of guides or track rails 19 that are inclined from their ends to their centers. In each side of the housing 13, within the respective endless flange 18, is an annular opening 20, the vertical axis of which is at the center of the track rail 19 thereof. Two oppositely projecting notches or short channels 21 extend from each opening 20 on radial lines that are parallel to the inclined surfaces of the track rails 19.

To return the roller 11 to normal position, there is provided a weighted centering pin 22 and a pair of wheels 23 that have rolling engagement with the guides or track rails 19. The pin 22 is of a much smaller diameter than the axial opening 12, through which it projects, to permit free radial movement of the roller 11 with respect thereto. The wheels 23 also have a smaller diameter than the openings 12, to permit the roller-returning member to be axially inserted therethrough to and from operative positions. As shown, the wheels 23 are cast integral

2
with the pin 22 slightly inward of its ends. The projecting ends of the pin 22 normally project into the openings 20 and, when the roller 11 is moved sufficiently to carry the 5 wheels 23 of the roller-returning member onto either of the inclines of the track rails 19, said projecting ends enter the respective channels 21.

To permit the escape of water, dirt, ice 10 and snow from the housing 13, there is formed in the sides thereof openings 24, the bottoms of which are below the upper surface of the lower bearing 10. Under extreme movements of the roller 11, the upper 15 inturned edges of the ends of the housing 13 afford stops 25 therefor. The end portions of the flanges 18 afford stops for the wheels 23 and the outer extremities of the notches or channels 21 afford stops for the 20 pin 22.

In the normal position of the roller 11, the pin 22 rests on the inner surface thereof and the wheels 23, as previously stated, rest on both of the inclines of the tracks 19. 25 The roller-returning member is held against endwise displacement from the roller 11 and housing 13 by its wheels 23, which extend below the bore 12 in said roller and the openings 20 in said housing.

30 In case the roller 11 is engaged by the upper bearing plate 9, when the car truck is on a curve, said roller will be moved thereby on the lower bearing plate 10 and carry with it the pin 22, thereby causing the wheels 35 23 to move upward on the respective inclines of the flanges or track rails 19. If the upper bearing plate 9 continues to rest upon the roller 11, until the car truck passes beyond the curve, said roller will be returned to 40 normal position under the action of the two bearing plates 9 and 10. But if the body bolster should lift with respect to the truck bolster and thereby carry the upper bearing plate 9 out of engagement with the 45 roller 11, while the same is on one of the inclines of the guides or tracks 19, said roller-centering device will, under the action of gravity, roll down the respective inclines, and, by its engagement with the 50 roller 11, return the same to normal position.

In assembling the improved side bearing, the roller 11 is first placed in the housing 13 and supported on the bottom thereof. 55 In this position of the roller 11, the opening 12 therein is in axial alinement with the housing openings 20. The roller-returning member is then inserted through one of the openings 20 and the opening 12 and its 60 wheels positioned on the guides 19. The roller 11 is then lifted, together with the roller-returning member which is carried thereby, to permit the bearing plate 10 to be inserted under said roller and placed on 65 the bottom of the housing between the lugs

16. Next, the rivets 17 are positioned in the bores provided therefor and upset to secure the bearing plate 10 in position. With the roller 11 supported on the bearing plate 10, its opening 12 is out of alinement with the 70 openings 20, and, to prevent the roller-returning member from being lifted and moved endwise through the roller 11, depending lugs 26 are formed on the flanges 18, as best shown in Figs. 4 and 5. Obviously, the member 10 not only serves as a bearing plate for the roller 11, but acts as a lock to prevent displacement of the anti-friction member and its returning member. Preferably, the roller 11 is cored out at 75 80

What I claim is:

1. In an anti-friction side bearing, the combination with upper and lower bearing plates, of an interposed roller, side walls associated with the lower bearing plate and 85 provided with guides inclined from both ends to the center, and a roller-returning member having on its ends wheels in rolling engagement with said guides, said roller-returning member loosely engaging said 90 roller and arranged by gravity to return the same to a central position.

2. In an anti-friction side bearing, the combination with upper and lower bearing plates, of an interposed roller, side walls 95 associated with the lower bearing plate and provided with guides inclined from both ends to the center, and a weighted centering member loosely engaging said roller and having on its ends wheels in rolling engagement- 100 with said guides.

3. In an anti-friction side bearing, the combination with upper and lower bearing plates, of an interposed hollow roller, or annular anti-friction member, side walls associated with the lower bearing plate and 105 provided with guides inclined from both ends to the center, and a roller-returning member loosely engaging said roller from the inside and having on its ends wheels 110 in rolling engagement with said guides.

4. In an anti-friction side bearing, the combination with upper and lower bearing plates, of an interposed hollow roller or annular anti-friction member, side walls associated with the lower bearing plate and provided with guides and openings above said guides, said guides being inclined from both ends to the center, and a roller-returning member loosely engaging said roller from the inside and having inward of its ends wheels in rolling engagement with the guides, the projecting ends of said roller-returning member extending into the openings in said side members and arranged to engage the ends thereof to limit the traveling movement of said member in either direction. 120 125

5. In an anti-friction side bearing, the combination with upper and lower bearing 130

plates, of an interposed roller, side walls associated with the lower bearing plate and provided with guides inclined from both ends to the center, and a roller-returning member having on its ends wheels in rolling engagement with said guides, said roller-returning member loosely engaging said roller and arranged by gravity to return the same to a central position, said wheels

in the centered position of the roller arranged to rest on the guides at both sides of the center.

In testimony whereof I affix my signature in presence of two witnesses.

EDWIN W. WEBB.
